[57] CLAIM

The ornamental design for a coin holder, as shown and described.

DESCRIPTION

FIG. 1 is a front perspective view of a coin holder showing my new design;

FIG. 2 is a top view of the coin holder shown in FIG. 1; FIG. 3 is a side elevational view of a first side of the coin holder shown in FIG. 1;

FIG. 4 is a side elevational view of a second side of the coin holder shown in FIG. 1;

FIG. 5 is a side elevational view of a third side of the coin holder shown in FIG. 1; and,

FIG. 6 is a side elevational view of a fourth side of the coin holder shown in FIG. 1.

The broken lines showing coin faces and state abbreviations are for illustrative purposes only and form no part of the claimed design.
